(57) **CLAIM**

The ornamental design for a charging stand for electronic devices as shown and described.

DESCRIPTION

FIG. 1 is a perspective view of a charging stand for electronic devices showing my new design;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof; and,
FIG. 9 is a perspective view of the charging stand for electronic devices shown in use.

The broken lines in the drawings depict portions of the charging stand for electronic devices, while the other broken lines in FIG. 9 are directed to environment. The broken lines form no part of the claimed design.
